(57) **CLAIM**

An ornamental design for a divider for medical apparatus and equipment, as shown and described.

DESCRIPTION

FIG. 1 is perspective view from above of our design of a divider for medical apparatus and equipment.

FIG. 2 is a perspective view from below of the divider for medical apparatus and equipment of FIG. 1.

FIG. 3 is a right side elevational view of the divider for medical apparatus and equipment of FIGS. 1 and 2.

FIG. 4 is a rear elevational view of the divider for medical apparatus and equipment of FIGS. 1-3.

FIG. 5 is a front elevational view of the divider for medical apparatus and equipment of FIGS. 1-4.

FIG. 6 is a top plan view of the divider for medical apparatus and equipment of FIGS. 1-5.

FIG. 7 is a bottom view of the divider for medical apparatus and equipment of FIGS. 1-6; and,

(Continued)

FIG. 8 is a left side elevational view of the divider for medical apparatus and equipment of FIGS. 1-7.
